(57) **CLAIM**

The ornamental design for a display screen or a portion thereof with a graphical user interface, as shown and described.

DESCRIPTION

FIG. 1 is a front view of a display screen or a portion thereof with a graphical user interface;

FIG. 2 is a front view of a second embodiment of a display screen or a portion thereof with a graphical user interface;

FIG. 3 is a front view of a third embodiment of a display screen or a portion thereof with a graphical user interface;

and

FIG. 4 is a front view of a fourth embodiment of a display screen or a portion thereof with a graphical user interface;

and,

FIG. 5 is a front view of a fifth embodiment of a display screen or a portion thereof with a graphical user interface. The outer broken-line rectangle shows a display screen or a portion thereof and forms no part of the claimed design. The remaining broken-lines illustrate portions of a graphical user interface and form no part of the claimed design.
